F. SCHAEFER

GASEOUS CONDUCTION LAMP

Filed Aug. 27, 1927

Fig. 3

BY Frank Schaefer
Chappell & Earl
AND ATTORNEYS

UNITED STATES PATENT OFFICE.

FRANK SCHAEFER, OF KALAMAZOO, MICHIGAN, ASSIGNOR OF ONE-HALF TO AMERICAN SIGNS CORPORATION, OF KALAMAZOO, MICHIGAN.

GASEOUS CONDUCTION LAMP.

Application filed August 27, 1927. Serial No. 215,882.

The main object of this invention is to provide a gaseous conduction lamp or "luminescent tube" which may be embodied in the form of a letter or other indicia for signs or ornamental purposes.

A further object is to provide a luminescent tube lamp structure which is economical to produce and one in which the finished product is attractive as there are no return bends in the main tube such as are commonly employed in forming letters having arms, or so-called block letters, as distinguished from script.

Objects pertaining to details and economies of my invention will appear from the description to follow. The invention is defined in the claims.

A structure embodying the features of my invention is clearly illustrated in the accompanying drawing forming a part of this specification, in which:

Fig. 1 is an illustration of a sign consisting of the word "AMSCO" embodying my invention.

Fig. 2 is a detail view partially in section of the letter "A" embodying the features of my invention.

Fig. 3 is a perspective view of the letter "K" embodying my invention.

Referring to the drawing, the structure illustrated in Fig. 1 is a lamp of the gaseous conduction type which consists of a tube designated generally by the numeral 1 and having electrodes 2 at its ends. This tube is adapted to contain a gaseous medium which glows or becomes incandescent when subject to electric currents on the use of certain so-called rare gases such as neon, helium and certain other gaseous mediums known in the art.

The letters or other indicia are formed of a main or outer tube either integral or integrally united. The letter "A" in the structure illustrated in Figs. 1 and 2, designated by the numeral 3, has an arm-like projection or branch 4 closed at its outer end. This branch 4 forms the closed portion of the letter.

In Fig. 1 the letter "C", designated by the numeral 5, also has an arm or branch 6 closed at its outer end, and the letter "O", designated by the numeral 7, has a similar arm or branch 8.

In Fig. 3 the letter "K", designated by the numeral 9, had the arm or branch por-

tions 10 and 11. This letter "K" is formed as a complete unit having electrodes 12 at its ends.

Referring to Fig. 2, it will be noted that the arm or branch 2 is of the same diameter 60 as the main tubular body of the letter. Disposed centrally within this branch is an inner tube 13 opening at its outer end adjacent the outer end of the arm 4.

The inner end of this inner tube is automatically joined to the walls of the main or outer tube at 14, thereby providing a return passage through the branch or arm. The same is true of the arms or branches 6 and 8 thereby providing a continuous passage including the branches or arms for the gaseous medium.

The outer tube is coated at 15 to render the tube at these points opaque so that the letters will appear as separate letters.

By this means I am able to form substantially any desired letter or luminous figure for use in signs or ornamental work with branches or arms where desired without folding the main tube upon itself as is the 80 universal practice so far as I am aware to produce such results or effect.

Lamps or structures embodying my improvements are very attractive in appearance, the inner tubes being invisible when 85 the lamp is in operation and, further, are not visible except on quite close inspection when the lamp is not in operation.

I have not attempted to illustrate or describe various adaptations of my improvements as it is believed that the disclosure made will enable those skilled in the art to adapt or embody my improvements as may be desired.

Having thus described my invention what 95 I claim as new and desire to secure by Letters Patent is:

1. A gaseous conduction lamp structure comprising a plurality of letters formed of an outer tube, certain of said letters having 100 arm-like parts closed at their outer ends, and inner tubes of a diameter smaller than that of said arm-like parts disposed centrally within such arm-like parts and opening thereto at their outer ends, the inner 105 ends of said inner tubes being expanded and joined to the walls of the outer tube providing a continuous passage, including the said arm-like parts, for a gaseous medium.

2. A gaseous conduction lamp comprising 110

an outer tube having a branch or arm closed at its outer end, and an inner tube of smaller diameter than said arm disposed therein with its outer end opening adjacent the outer end of said arm, its inner end being joined to the outer tube at one side of the arm providing a continuous passage for a gaseous medium adapted to glow when subjected to an electric discharge, and electrodes disposed at the ends of said outer tube.

3. A gaseous conduction lamp comprising an outer tube having arm-like parts closed at their outer ends, and inner tubes of less diameter than such arm-like parts disposed centrally therein and with their outer ends opening adjacent the outer ends of such arm-like parts, and their inner ends autogenously joined to the walls of the outer tube at points in advance of the arm-like parts providing return passages in such arm-like parts open to the main passage.

4. A gaseous conduction lamp comprising a main or outer tube having a branch closed at its outer end, and an inner tube of less diameter than said branch disposed centrally therein and with its outer end opening adjacent the end of such branch, the inner

end of said inner tube being autogenously joined to the wall of the outer tube in advance of the branch, closing the main passage in the tube and providing a continuous passage, including said branch, for the gaseous medium.

5. A gaseous conduction lamp comprising an outer tube having an arm-like part closed at its outer end, and an inner tube of less diameter than such arm-like part disposed therein and with its outer end opening adjacent the outer end of such arm-like part and its inner end joined to the wall of the outer tube at one side of the arm-like part providing a return passage in such arm-like part open to the main passage.

6. A gaseous conduction lamp comprising a main or outer tube having a branch closed at its outer end, and an inner tube disposed within said branch with its outer end opening adjacent the end thereof, the inner end of said inner tube being secured to the wall of the outer tube at one side of the branch providing a continuous passage, including said branch, for the gaseous medium.

In witness whereof I have hereunto set my hand.

FRANK SCHAEFER.
